UNITED STATES PATENT OFFICE.

HENRI SÉVÈNE AND EMILE DAVID CAHEN, OF PARIS, FRANCE.

MACHINE FOR BOXING MATCHES.

SPECIFICATION forming part of Letters Patent No. 643,072, dated February 6, 1900.

Application filed August 2, 1898. Serial No. 687,562. (No model.)

To all whom it may concern:

Be it known that we, HENRI SÉVÈNE and EMILE DAVID CAHEN, citizens of the Republic of France, residing in Paris, France, have 5 invented new and useful Improvements in Mechanical Boxing of Matches, of which the following is a specification.

The apparatus that forms the subject-matter of this invention has for its object the mechanical boxing of matches. It can be adapted to various machines of continuous manufacture. It receives, on the one hand, the manufactured and expelled or stripped matches and, on the other hand, the drawers and slides 15 and delivers the boxes filled and closed.

We indicate hereinafter the way in which our invention may be practically carried out. We will describe it in detail with reference to the annexed drawings and then sum up 20 its salient characteristics in the claims.

Figures 1 and 1^a taken together represent a longitudinal elevation of the apparatus with certain parts removed. Figs. 2 and 2^a taken together represent a sectional plan according 25 to the line 2 2 of Fig. 1. Fig. 3 is a vertical section according to the line 3 3 of Fig. 1, the pedestals of the shaft N being removed. Fig. 4 is a vertical section according to the line 4 4 of Fig. 1 on a larger scale than the previous 30 figures. Fig. 5 is a vertical section according to the line 5 5 of Fig. 1, to the same scale as that figure, the observer being placed on the left of the plane of section. Fig. 6 is a view of a cell, to the same scale as Fig. 4, the observer 35 being placed according to the line 6 6 of Fig. 4, the guides being removed.

By way of example our improved apparatus is represented in the accompanying drawings as placed before the endless chain A of 40 a machine for making matches.

A series of punches of any suitable kind (not shown in the drawings) strips the matches contained in the chain or press and drives them forward upon the table B of the apparatus, Figs. 1, 2, and 4. This table B is fixed to the framework X and consists of a series of horizontal stirrups B', of L form, furnished at their upper and lower parts with metal sheets or plates B² and B³, so as to constitute a box closed on five faces and open 45 only at the face turned toward the chain or press. Two of these boxes have each lodged

therein a lever B⁴, journaled on an axle B⁵, fixed between the branches of the stirrup B'. One of the ends b of the lever is split or 50 forked in such a manner as to embrace a pin b² of a second lever B⁶, controlled by the lever B⁴. This lever B⁶, journaled about the axle B⁷, likewise fixed between the branches of the stirrup B', has its first branch traversed 55 by the pin b², as has been said above. It carries by its other branch a small angle-piece B⁸, which in the movement of the lever B⁶ oscillates about the axle B⁷. The space comprised between two consecutive stirrups B' 60 forms a well C, limited on the right and on the left by the vertical faces of the stirrups, at the back by an angle-piece c', and in front by a piece c², forming an inclined plane between the stirrups. The second branch b³ of 65 the lever B⁴ is bent over and passes into a notch d' of a piece D, constituting a rake-carrier. This rake-carrier is furnished with branches D', perpendicular to its axis, in number equal to that of the wells. These branches 70 D' or rakes are terminated at their lower part by teeth D², which slide on the upper metal sheets or plates B² of the table B in the movement of the rake-carrier. The latter has the form of a horizontal L, whose two small 75 branches d² slide in a groove D³ and whose large branch d³ rests on a rabbet D⁴ of the framework. The notches d' are profiled in the form of ramps which bear on the head b³ of the levers B⁴, so that the levers B⁴ fall or 80 rise, according as the lower or upper part of the ramp slides on their head b³.

The to-and-fro movement of the rake-carrier may be obtained in any suitable way and in particular as hereinafter described. A 85 button D⁵, fixed to one of the small branches d² of the rake-carrier, is seized by a fork E', cut in the end of a lever E, whose other end journals about an axle E², fixed to the framework. The lever E carries an axle E³ and with 90 a roller thereon that engages in the groove of a cam E⁴, keyed on an intermediate shaft N. This intermediate shaft N revolves in pedestals N', supported by the framework. It receives its motion from the main shaft M 95 through toothed wheels M² and N², the shaft M being itself supported by pedestals M', fixed to the framework and receiving its motion either from other parts of the principal

machine through any suitable connection or directly through a transmission-belt.

The following is the operation of this part of the apparatus: In the state of rest the lower part of the ramps d' being in contact with the head b^3 of the levers b^4 the upper wing of the angle-pieces B^8 is inclined, as indicated in Fig. 4, and its upper edge touches the chain or press A. The stripping system of the match-making machine acting at this moment projects a series of matches upon the table B^2 . The cam E^4 then actuating the lever E causes the rake-carrier D and the rakes to move. When the latter have effected a part of their travel, the ramps d' permit the first branch of the levers B^4 to rise. The second branch of the said levers acting upon the pin b^2 causes the levers B^6 to turn and place the inclined wing of the angle-piece B^8 in a vertical position, so that the matches that were able to rest supported on the angle-piece are brought back upon the table B. The rakes D', continuing their forward movement, drive the matches before them into the wells C and cause them to fall into the cells F' of the chain F, which will hereinafter be described. The successive inclined planes of the different pieces and angle-pieces D c' f' (on the left) B⁸ B⁶ c² (on the right of Fig. 4) are arranged stepwise in the horizontal sense as well as the vertical, so as to gather the matches toward the center of the drawer and to prevent the matches from being projected laterally out of the wells during their fall.

The drawers are placed in the right-hand part of the cells of the chain F, Fig. 4. This chain is constituted in the following fashion, Figs. 1, 2, 3, 4, 5, and 6: Axles F² are connected somewhat in the form of a bicycle-chain by links F³. Their ends can be furnished or not with rollers. They each carry a cell F', composed of a medium web F⁴, supporting at the upper part a cup F⁵ and at the lower part a roller F⁶. The cup is divided into two parts. The left-hand part, Fig. 4, closed at the top by a plate F⁷, forming a cover, carries four very flexible springs F⁸, two vertical and two horizontal, fixed to the sides of the cup near its middle. The right-hand part is open. Its lateral edges are raised and carry two very thin oblique springs F⁹. Each slide is introduced endwise into the left-hand part of a cup and passes as a sleeve upon or outside of the four springs F⁸, which converge toward its center. A drawer is placed at the right hand of a slide in each cup. The springs F⁹ are sufficiently flexible to permit its introduction. On the other hand, they oppose the vertical rising of the drawer that has been inserted, and they sufficiently cover its edges to prevent the matches from being introduced into the free space that exists between the walls of the cell and the sides of the drawer. The supplying of the cups with empty drawers and slides may be done in any suitable manner, either by hand or mechanically. Grooves F¹⁰ are

made at the four corners of the cups and extend over their whole length. Stops F¹¹, of metal or of leather, fixed on the links F³, limit the oscillations of the cells. The chain is closed. It rolls upon two pairs of lantern-wheels G G' and is supported throughout its length by slides G², fixed to the general framework X by feet G³. The lantern-wheels G G' are fixed on shafts O and P, revolving in pedestals O' and P', fixed to the framework X by supports Y. The two shafts O and P are connected by an auxiliary shaft Q, supported by pedestals Q', fixed to the framework Y, and bevel-wheels O² P² Q², so as to revolve synchronously. The rotary motion can be communicated to one of the two shafts O or P in any suitable way, herein shown by two spur-wheels M³ P³, keyed, respectively, on the shafts M and P. A part of the toothed periphery of the wheel M³ is removed, so that the wheel P³ turns only a fraction of a revolution to each revolution of the shaft M. The shaft P and the lantern-wheel G' turn the same fraction of a revolution as the wheel M³, it may be by a quantity precisely equal to the pitch of the chain, so that all the cells F' advance one rank or step at each revolution of the main shaft M.

In order to keep the cell-chain fixed during the intervals of time in which the wheel P³ does not rotate, there can be employed an arrangement consisting, for example, of a disk M⁴, with notch m, keyed on the shaft M, and a star-wheel P⁴, keyed on the shaft P. This arrangement operates by intermissions in the ordinary way.

The pitch of the chain is in accordance with the distance apart of two wells C C', so that at each stoppage of the chain a cell is under each well. The number of the cells and their forward movement are combined, so that the boxes are completely filled after their passage under all the wells that feed them. For example, to obtain boxes containing one hundred and four matches there can be employed a table B, with eight wells C, and a chain whose pitch is equal to the interval that separates two consecutive wells. Each stripping stroke causes thirteen matches to fall on each portion of the table, and each drawer comes successively to receive these thirteen matches in its passage under each well.

Two bars H, provided with bell-mouthed notches H', Figs. 1, 4, and 5, corresponding to the position of rest of the cells, are capable of receiving a reciprocating vertical movement. When they are lowered they leave the chain free to pass, but when they are raised the notches embrace the ends of the axles F² and fix them in their position of rest, the notch constituting the female part of a bolt or lock, the male part of which is represented by the axle of the chains. The upward and downward movement of these bars can be obtained in any suitable manner and in particular in the following manner: Each of these bars is guided by two small slides H²,

which prevent their inclination and their lateral deviation. At each of the ends of the bars H a lever H³ carries a roller h, which bears against a cam H⁴, keyed on the shaft N. 5 One of each lever is journaled by an axle H⁵, mounted on a support H⁶, fixed to the framework X. The cam oscillates the lever, whose other end sustains the corresponding bar H. The bars H follow, then, the movements of the 10 levers H³. The cams are cut so as to raise the bars H simultaneously at the desired moment to fix the axles of the cells in their position of rest. When the cells are in their position of rest, the lower rollers F⁶ engage in the sinusoidal groove I' of cams I, keyed on the shaft N opposite to each cell. In the rotary movement of this shaft the grooves of the cams I impart to the cells a shaking movement, which communicates itself to the matches assembled in the drawers on their passage under the wells. This shaking arranges the matches and classes them in the drawers. The general arrangement of the chain and of the cells is advantageous, in that it allows 20 each cell to be shaken singly and solely at the proper moment, which avoids the difficulties and the shocks that are entailed by the general shaking of the chain. Moreover, this individual shaking of each cell allows another 25 result—viz., the grooves gradually separate from the median plane of the cams when the chain advances, so that the amplitude of the oscillations decreases in accordance with the filling of the boxes, a condition which is favorable to the classing of the matches and 30 which prevents their projecting out of the drawers when they are on the point of being filled up. The groove is interrupted at I' on the cams, the periphery of which has a smooth 35 cavity sufficiently extended to allow the roller F⁶ to disengage itself from the cam and to present itself above the following one when the chain advances during the rotation 40 of the shaft N. When each drawer has 45 passed successively under all the wells, it is filled with matches well classed and settled as a result of the successive shakings of the cams I, after which it presents itself opposite to a piston J, having a horizontal to-and-fro 50 movement perpendicular to the advance of the chain F. This piston, whose height and width are less than those of the cups to enable it to enter freely therein, carries four ribs J', corresponding to the grooves F¹⁰ of the cups. 55 It slides in the guide J², connected to the framework X by a support J³. The ribs J' are such that the total width of the piston (including the said ribs) is greater than that of the drawers and of the slides, so that the 60 piston when it arrives in contact with the drawers and the slides attacks them on all their corners, (more rigid than the body of the box itself,) which prevents their deformation at the moment of being pushed. 65 The movement of the piston J can be obtained in any suitable way—for example, as follows: A lever K, jointed at one of its ends to an axle K', fixed to a support K² of the framework X, carries a roller K³, which travels in the groove of a cam K⁴, keyed on the shaft 70 M. The other end of the lever K', which is formed as a fork, embraces an axle J⁴, provided on or integral with the piston J, and thus carries it along with it in its to-and-fro movement. The cells F' carry a spur F¹², cut 75 in the manner of a double inclined plane f' f² under the floor of the cups F⁵. The fixing-bars H carry on their sides a peak H⁷, cut cornerwise opposite the piston J. It will be obvious that in the upward movement of the 80 bars H their peak H⁷ is introduced into the spur F¹² of the cell which becomes stopped opposite to the piston J. The spur F¹² thus represents the female part of a bolt, of which the male part is the peak H⁷. The cell is 85 thus fixed in the position most favorable for the introduction of the piston J. A similar arrangement is found at the other end of the bar H at the place where the drawers and the slides are introduced into the cells in order 90 to fix the said cells at the moment of this introduction. In line with this piston J, but at the other side of the chain, there is an inclined passage L, fixed to the framework X by an angle-piece L'. A hinge-door L², capable of 95 pivoting about an axle l integral with the passage L, can either be fixed in a vertical position, as illustrated in Fig. 3, or be turned back obliquely, according to the inclination of the bottom of the passage L. The oscillating movement of this door can be obtained in any manner whatever—for example, as follows: A lever L³, whose one end turns about an axle b', fixed to a support L⁴ on the framework X, carries a roller L⁵, which bears against 100 the periphery of cam L⁶, keyed on the shaft N. The other end of the lever L³ is jointed by an axle l² to the lower part of a connecting-rod L⁷, which controls the door L² by a joint l³. The cam L⁶ oscillates the lever L³, which controls the connecting-rod L⁷ and consequently 105 the door L². 110

The following is the operation of this last part of the apparatus: Each cell containing a drawer and slide passes successively under 115 the different wells C. Under the first cell the drawer collects the first series of matches, which as a result of the shaking of the cams I are classed at the bottom of the drawer. During the advance of the chain F the cell 120 passes under the second well, where a second series of matches is classed upon the first, then a third, and so on. After its passage under the last well the drawer is full of matches, classed and well settled. Some instants later 125 the cell presents itself opposite to the piston J. It is fixed in its boxing position by the bar H and the peak H⁷. The door L² is in the vertical position and forms a stop for the slide. The piston J advances. It drives before it 130 the drawer, which is forced to pass into the slide, by the springs F⁸, which form a funnel. At the moment when the drawer is completely introduced into the slide the door L² pivots.

It is now out of the way against the bottom of the passage L. The piston J, continuing its advance movement, expels through the passage the box which is completely finished.

5 Having now particularly described and ascertained the nature of the said invention and in what manner the same is to be performed, we declare that what we claim is—

1. An apparatus for boxing matches, comprising an endless chain consisting of cells constructed and adapted to receive the slides and drawers and capable of oscillation individually, with means for producing the oscillation of each cell, and means for introducing 10 the drawers into the slides, and to expel the finished boxes.

2. In apparatus for boxing matches an endless chain F composed of cells F', provided with four carrying-springs F^g forming funnels 20 on which the slides may be placed as sleeves substantially as and for the purposes described.

3. In apparatus for boxing matches, a chain composed of cells capable of individual oscillation, each of said cells being provided with a stem, in combination with a rotating shaft having grooved cams mounted thereon in 25 which the said stems engage, substantially as described.

30 4. In apparatus for boxing matches, a chain composed of cells capable of individual oscillation, each of said cells being provided with a stem and with a spur cut with a double incline plane, in combination with a rotating 35 shaft having grooved cams mounted thereon

in which the said stems engage, and bars provided with peaks to enter the said double incline planes, substantially as and for the purposes set forth.

5. In apparatus for boxing matches, the 40 combination of a chain of cells F' with grooves F¹⁰ with a piston J having ribs J', substantially as described.

6. In apparatus for boxing matches, the combination of an endless chain provided 45 with cells, each adapted to carry the slide and drawer of a box, and a piston to close the box and expel it from the cell, with a passage for the outlet of the closed boxes, and a movable door for said passage, adapted to form a stop 50 opposed to the said piston while closing the box, and then to open the said passage for the outlet of the box, substantially as set forth.

7. In apparatus for boxing matches, the combination of a chain of cells each provided 55 with a grooved chamber to receive the boxes, and a piston having ribs extending beyond the boxes and into the grooves of the chamber, with a passage provided with a movable door adapted to form a stop while the piston 60 is closing the box, substantially as set forth.

In testimony whereof we have signed our names to this specification in the presence of two subscribing witnesses.
